UNITED STATES PATENT OFFICE.

JOSEPH L. DAVIS, OF ABINGDON, ILLINOIS.

TEMPERATURE REGULATOR FOR INCUBATORS.

Application filed August 5, 1926. Serial No. 127,380.

This invention relates to temperature regulators for incubators and more particularly to a device of this character for use with that type of incubator where the temperature of the incubator is controlled by a valve regulating the flow of heated water through the incubator.

Incubators of this type are what are known as mammoth incubators and are 10 adapted for the simultaneous production of a great number of chicks. The incubator is of considerable size and the ordinary regulator employed is both crude in its adjustment and difficult of access. Accordingly, 15 an important object of the present invention is to provide a device of this character which may be conveniently located, which permits a very delicate adjustment of the temperature and which will not in any way interfere 20 with the normal operation of the incubator.

A further object of the invention is to provide a device of this character which may be attached to the present incubator constructions without in any manner altering 25 the same.

These and other objects I attain by the construction shown in the accompanying drawings, wherein for the purpose of illustration is shown a preferred embodiment of 30 my invention and wherein:

Figure 1 is a side elevation partially broken away of an incubator showing a regulator constructed in accordance with my invention applied thereto;

Figure 2 is an enlarged vertical sectional view on the line 2—2 of Figure 1.

Referring now more particularly to the drawings, the numeral 10 generally designates a mammoth incubator interiorly of 40 which are arranged heating coils 11. Exteriortly of the incubator is arranged a heater 12 by means of which water within a tank 13 is kept heated and the upper and lower ends of this tank are connected by

45 conduits 14 and 15 with the terminals of the coils 11. The temperature regulation is provided by installing within the incubator a thermostat 16 through which oscillation of the pivoted lever 17 supported from the top 50 of the incubator, as at 18, is obtained in the usual manner. Arranged within the conduit 14 which communicates with the inlet of the coil 11 is a valve 18^a, the bonnet of which is secured thereto a vertically extending tube 19, the upper end of which projects 55 above the highest point of the water circu-

lating system and is in direct communication with the valve seat. The valve element 20 of the valve has its stem 21 connected with one end of the lever, as at 22, so that when 60 this end of the lever is depressed, the valve is seated and circulation through the coil is cut off.

The above structure all forms a normal part of the incubator construction and is not 65 a part of my invention except in combination with the features hereinafter described. In accordance with my invention, I provide a sleeve 22 adapted to exteriorly fit the upper end of the tube 19 and be secured thereto. In the present instance, set-screws 23 are illustrated as the securing means. This sleeve has diametrically opposed outstanding ears 24 from which extend vertically disposed rods 25, the upper ends of which are 70 threaded. To the valve stem 21, I secure a spring seat 26 against which abuts one end of a spring 27. A cross bar 28 is provided having an opening for the passage of the valve stem 21 and a seat 29 for the upper end 75 of the spring. The opposite ends of this cross bar have openings 30 for the passage of the threaded upper ends of the rods 25 and nuts 31 are employed to force the bar 80 downwardly toward the tube 19 and the seat 32 of the valve. In the present instance, the ends of the bar are shown as horizontally slotted, as at 33, and the nuts 31 as being disposed within the slots, so that the position 85 of the bar is positively determined and any misplacement of the bar by an accidental engagement therewith prevented. It will be 90 obvious that by adjusting the nuts 31, the pressure which the spring 27 exerts to seat the valve 20 may be very closely regulated 95 and accordingly the temperature of the interior of the incubator closely regulated.

Since the structure hereinbefore set forth is obviously capable of a certain range of change and modification without materially departing from the spirit of the invention, I 100 do not limit myself to such specific structure except as hereinafter claimed.

I claim:

1. The combination with an incubator including a heating coil and a heating tank supplying the coil, a valve controlling circulation through the tank and coil and a thermostatically controlled lever for shifting the valve, a member embodying rods paralleling the stem of the valve secured in fixed 105 relation to the valve casing, a spring seat 110

secured to the valve stem below the upper ends of the rods, the upper ends of said rods being threaded, a cross bar having an opening for the passage of the valve stem at its center and openings for the passage of the rods at its ends, a spring extending between the valve seat and cross bar and surrounding the valve stem and nuts upon the upper ends of the rods for shifting the cross bar toward said spring seat.

2. The combination with an incubator including a heating coil and a heating tank supplying the coil, a valve controlling circulation through the tank and coil and a thermostatically controlled lever for shifting the valve, a member embodying rods paralleling the stem of the valve secured in fixed relation to the valve casing, a spring seat secured to the valve stem below the upper ends of the rods, the upper ends of said rods being threaded, a cross bar having an opening for the passage of the valve stem at its center and openings for the passage of the rods at its ends, a spring extending between the valve seat and cross bar and surrounding the valve stem and nuts upon the upper ends of the rods for shifting the cross bar toward said spring seat, the rod engaging ends of said cross bar having horizontal slots within which said nuts are located.

3. The combination with an incubator including a heating coil and a heating tank supplying the coil, a valve controlling circulation through the tank and coil and a thermostatically controlled lever for shifting the valve, a member embodying rods paralleling the stem of the valve secured in fixed relation to the valve casing, a spring seat secured to the valve stem below the upper ends of the rods, the upper ends of said rods

being threaded, a cross bar having an opening for the passage of the valve stem at its center and openings for the passage of the rods at its ends, a spring extending between the valve seat and cross bar and surrounding the valve stem and nuts upon the upper ends of the rods for shifting the cross bar toward said spring seat, the valve casing having a tubular extension through which the valve stem is directed, said member including a sleeve fitting the upper end of the tubular extension of the casing and secured thereto.

4. The combination with an incubator including a heating coil and a heating tank supplying the coil, a valve controlling circulation through the tank and coil and a thermostatically controlled lever for shifting the valve, a member embodying rods paralleling the stem of the valve secured in fixed relation to the valve casing, a spring seat secured to the valve stem below the upper ends of the rods, the upper ends of said rods being threaded, a cross bar having an opening for the passage of the valve stem at its center and openings for the passage of the rods at its ends, a spring extending between the valve seat and cross bar and surrounding the valve stem and nuts upon the upper ends of the rods for shifting the cross bar toward said spring seat, the rod engaging ends of said cross bar having horizontal slots within which said nuts are located.

5. The combination with an incubator including a heating coil and a heating tank supplying the coil, a valve controlling circulation through the tank and coil and a thermostatically controlled lever for shifting the valve, a member embodying rods paralleling the stem of the valve secured in fixed relation to the valve casing, a spring seat secured to the valve stem below the upper ends of said rods having horizontal slots within which said nuts are located, the valve casing having a tubular extension through which the valve stem is directed, said member including a sleeve fitting the upper end of the tubular extension of the casing and secured thereto.

In testimony whereof I hereunto affix my signature.

JOSEPH L. DAVIS
